(57) **CLAIM**

The ornamental design for an agitator for pharmaceutical compounding, as shown and described.

DESCRIPTION

FIG. 1 is a perspective top view of the agitator for pharmaceutical compounding. The view from the opposite side being identical thereto.

FIG. 2 is a perspective bottom view of the agitator for pharmaceutical compounding with the cap in place.

FIG. 3 is a top plan view of the agitator for pharmaceutical compounding.

FIG. 4 is a bottom plan view of the agitator for pharmaceutical compounding.

FIG. 5 is a side elevational view of the agitator for pharmaceutical compounding with the cap in place; and, FIG. 6 is a cross sectional view taken at line 6-6 of FIG. 3.

1 Claim, 1 Drawing Sheet
